(57) **CLAIM**

The ornamental design for measuring tray, as shown and described.

DESCRIPTION

FIG. 1 is a perspective view of the measuring tray; FIG. 2 is a front view of the embodiment of FIG. 1; FIG. 3 is a back view of the embodiment of FIG. 1; FIG. 4 is a right side view of the embodiment of FIG. 1; FIG. 5 is a left side view of the embodiment of FIG. 1; FIG. 6 is a top view of the embodiment of FIG. 1; and, FIG. 7 is a bottom view of the embodiment of FIG. 1. The broken lines, and the unshaded surfaces within, illustrate portions of the measuring tray and form no part of the claimed design.
